(57) **CLAIM**

We claim the ornamental design for a mobile terminal, as shown and described.

DESCRIPTION

FIG. 1 is a front perspective view of a mobile terminal showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view, in which the mobile terminal is provided in a first alternate position;

FIG. 9 is a front view thereof;

FIG. 10 is a rear view thereof;

FIG. 11 is a top view thereof;

FIG. 12 is a bottom view of thereof;

FIG. 13 is another front perspective view, in which the mobile terminal is provided in a second alternate position;

FIG. 14 is a front view thereof;

FIG. 15 is a rear view thereof;

FIG. 16 is a top view thereof;

FIG. 17 is a bottom view thereof;

FIG. 18 is another front perspective view of FIG. 1, in which a cover in broken lines is provided to illustrate an example environment; and,

FIG. 19 is another front perspective view, in which the mobile terminal is provided in a third alternate position and a cover in broken lines is provided to illustrate an example environment.

The broken lines shown in the figures that are immediately adjacent to the shaded areas and define unshaded regions represent the bounds of the claim. All other broken lines, that
